UNITED STATES PATENT OFFICE.

EDWIN C. YAUCK, OF COLUMBUS, OHIO.

STAMP-AFFIXER.

No. 874,720.

Specification of Letters Patent.

Patented Dec. 24, 1907.

Application filed March 9, 1907. Serial No. 361,680.

To all whom it may concern:

Be it known that I, EDWIN C. YAUCK, a citizen of the United States, residing at Columbus, in the county of Franklin and State 5 of Ohio, have invented certain new and useful Improvements in Stamp-Affixers, of which the following is a specification.

My invention relates to stamp affixers and has for its object the provision of a device of 10 this character constructed in such manner that it may be very cheaply manufactured and will be adapted to manipulate sheets of stamps, the invention comprising means for feeding the stamps between cutting edges, 15 moistening the stamps, cutting the individual stamps from the sheets and pressing said stamps into engagement with the letters or other mail matter to which said stamps are to be affixed.

20 A further object of the invention is the provision of a device of this character constructed in such manner that two stamps may be fed into position above the letter to be stamped before said stamps are cut from 25 the sheet, by virtue of which construction it is possible to stamp a letter requiring four cents postage at a single stroke of the plunger, hereinafter described.

Further objects and advantages of the invention will be set forth in the detailed description which now follows.

In the accompanying drawings: Figure 1 is a front elevation of a stamp affixer constructed in accordance with the invention, 35 Fig. 2 is a rear elevation of said stamp affixer, Fig. 3 is an end elevation looking toward the left in Fig. 1, with the hand wheel of the feed roller indicated in dotted lines, Fig. 4 is a detail view of a ratchet bar and its 40 actuating and stop members hereinafter described, and, Fig. 5 is a side elevation of the stop member of the ratchet bar.

Like numerals designate corresponding parts in all of the figures of the drawing.

45 Referring to the drawing, the numeral 5 designates a base which may be of any desired form. Secured to this base by fastening devices 6, is a standard 7. This standard carries at its upper end a plate or table 8.

50 A plunger plate 9 is located beneath the plate 8 and rods 10 which are connected to said plunger pass through said plate. A cap 11 is mounted upon the upper ends of these rods and a spring 12 which bears between 55 said cap and the plate 8, normally tends to hold the plunger plate 9 in an elevated posi-

tion. A standard 13 which is secured to the base 5 by a screw 14, terminates in a table 15, this table being adapted to receive the letters that are to be stamped. An extension 16 60 carries a vertically movable stop member 17. This stop member is best illustrated in Fig. 5. By referring to said figure, it will be seen that it is slotted as at 18 and is normally held in an elevated position by a flat spring 19. Pins 65 20 which pass through the slot 18 retain this stop member in position, said stop member serving a purpose which will be hereinafter described. The plunger plate 9 has a rearwardly extending portion 9' which overlies the 70 upper end of a U-shaped member 21. One of the legs of this U-shaped member enters a cylinder 22 and forms a plunger within said cylinder, this plunger and cylinder acting as an air pump to force air through the flexible 75 tube 22' and nozzle 23 of an atomizer 24, said atomizer being adapted to receive a suitable liquid for moistening the stamps. The other arm of the U-shaped member is bifurcated as at 25 and straddles a crank arm 26 80 of a rod 27, said rod being journaled in the standard 7 and in an ear 28 which extends from a web 29. This web 29 is carried by the standard 7 and lies at right angles thereto and it is from this web that the extension 16 85 projects.

A grooved roller 30 is journaled in an ear 31 of the web 29. A second grooved roller 32 is journaled in an ear 33 of the standard 13. These two rollers lie in the same horizontal plane and receive the lower edge of a plate 34 which forms a portion of a movable carriage. A third grooved roller 35 is journaled in an ear 36 of the table 8. The plate 34 (see Figs. 1 and 3) is longitudinally slotted at 37 and the metal at the upper edge of said slot is bent outwardly as at 38. The metal at the lower edge of the slot is bent out at right angles to the plane of the plate 34 as at 39, to form a cutting edge which is 90 adapted to co-act with the edge 40 of the plunger plate 9. Secured to the rear face of the plate 34 is a guide and shield plate 41. The ends of this guide plate 41 are bent upwardly as at 42 and journaled in these bent-up ends is a feed roller 43. This feed roller is mounted upon a shaft 44 and a hand wheel 45 secured to said shaft provides means for turning said roller to feed the sheet of stamps illustrated by the dotted line 46 in Fig. 3, 110 across the cutting edge 39, said sheet of stamps passing between the roller 43 and the

plate 41. A ratchet bar 47 is journaled in ears 48 which project from the rear face of the plate 34. An upturned lever 49 provides means for rocking the ratchet bar in the ears 5 as will be hereinafter described. The rod 27 is provided with an upwardly extending portion 50 (see Figs. 3 and 4). Secured to the upper end of this portion 50 by fastening devices 51 is a light spring plate 52 which is 10 adapted to ride over the inclined faces 53 of the ratchet bar 47, as is illustrated in dotted lines in Fig. 4 and to snap behind the shoulders 58 of said ratchet bar to move the carriage longitudinally. A coiled spring 59 15 which is coiled about the rod 27 normally tends to throw the extension 50 of said rod toward the right in Fig. 2.

The operation of the device is as follows: A sheet of stamps having been placed in the 20 position illustrated by the dotted line 46 in Fig. 3 and fed forwardly until the perforated line between the first row of stamps and the second row of stamps lies over the cutting edge 39, the operator strikes upon the cap 11 25 to force the plunger plate 9 downwardly. By referring to Fig. 2, it will be seen that the notches of the ratchet bar 47, extend beyond the ends of the stamp sheet. When the carriage, therefore, is moved to its limit of 30 movement toward the left in Fig. 2, the first stamp to be cut off, will not lie beneath the plunger, but will lie in position to be sprayed by the atomizer when the plunger 11 is first depressed. The first depression of the plunger 35 therefore will not sever a stamp, but will spray and moisten a stamp and move said stamp into such position that it will be severed from the sheet upon the next depression of the plunger. A letter is then placed in 40 position resting upon the table 15 and the plunger is again depressed. This depression of the plunger sprays a second stamp and cuts off the first stamp, said first stamp being pressed into engagement with the letter by 45 the plunger plate 9. The longitudinal feed of the carriage is accomplished by the arm 50, said arm moving toward the left in Fig. 4, upon the depression of the plunger, through the connections described and being thrown 50 to the right by the spring 59 when said plunger is released. The cylinder 22 not only acts as an air pump upon the depression of the plunger, but it acts as a retarding device to prevent the carriage from moving too 55 quickly when said plunger is released. The spring 12 acts to force the plunger plate 9 to its elevated position as soon as the operator removes his hand from the cap 11, but the forward movement of the carriage is slower 60 by reason of the fact that the pump formed by the cylinder 22 and its plunger, acts as a retarding element to the action of the spring 59 in moving the carriage forward. This result is attained by reason of the fact that the 65 end of the crank arm 26 underlies the bifur-

cated end of one of the legs of the U-shaped member 21. Since the other leg of this U-shaped member enters the cylinder 22 and operates as a pump plunger therein, it follows that this U-shaped member will be retarded during its upward movement by the vacuum in the cylinder 22, the atmospheric pressure upon the top of the plunger tending to hold said plunger down until air finds its way to the cylinder through the atomizer. 70 Retarding the upward movement of the U-shaped member 21 in this manner, of course retards the movement of the carriage, for the movement of the carriage is controlled by the throw of the crank arm 26. 80

If it be desired to place two stamps upon a letter, a handle 60 carried by the U-shaped member 21, may be grasped and depressed to feed the carriage forward the extra notch to bring the extra stamp above the table 15, 85 after which the depression of the plunger plate 9 will serve to sever these two stamps and press them into engagement with the letter. The stop member 17 is provided for the purpose of preventing retrograde movement of the carriage during the time that the light spring plate 52 is moving across the inclined face 53 of the ratchet bar. 90

After a row of stamps has been severed from the sheet, the carriage may be returned to its limit of movement toward the left in Fig. 2, by the operator grasping the lever 49 and rocking the ratchet bar in the ears 8 to throw said ratchet bar out of engagement with the stop member 17 and the spring 100 plate 52. 95

The retarding of the movement of the carriage effected by the action of the plunger in the cylinder 22, prevents the carriage from moving forward quickly enough to cause the 105 next stamp to catch upon the plunger plate 9, said plunger plate having ample time to assume its elevated position before the forward movement of the carriage is effected.

From the foregoing description, it will be 110 seen that simple and efficient means are herein provided for accomplishing the objects of the invention, but while the elements shown and described are well adapted to serve the purposes for which they are intended, it is to be understood that the invention is not limited to the precise construction set forth, but includes within its purview such changes as may be made within the scope of the appended claims. 115

What I claim, is,

1. In a device of the character described, the combination with a supporting frame, of a vertically movable plunger, means normally tending to elevate said plunger, 125 said plunger being provided with a cutting edge, a longitudinally movable carriage, a cutting edge formed upon said carriage with which the cutting edge of the plunger co-acts means carried by the carriage for feeding a 130

sheet of stamps between said cutting edges, an atomizer, and an air pump actuated by the depression of the plunger for spraying liquid from said atomizer upon said stamps, 5 said pump serving to retard the movement of the carriage.

2. In a device of the character described, the combination with a supporting frame, of a vertically movable plunger, means normally tending to elevate said plunger, said plunger being provided with a cutting edge, a longitudinally movable carriage, a cutting edge formed upon said carriage with which the cutting edge of the plunger co-acts, 10 means carried by the carriage for feeding a sheet of stamps between said cutting edges, an atomizer, an air pump actuated by the depression of the plunger for spraying liquid from said atomizer upon said stamps, means actuated by the plunger for imparting a step by step movement to the carriage, and a stop member for preventing retrograde movement of said carriage, the air pump serving to retard the movement of the carriage.

25 3. In a device of the character described, the combination with a supporting frame, of a vertically movable plunger, a spring normally tending to hold said plunger in an elevated position, a longitudinally movable carriage, a cutting edge formed upon said carriage which extends the width of the sheet of stamps to be cut, a feed roller carried by the carriage and adapted to feed said sheet of stamps over said cutting edge, an atomizer arranged to spray said stamps, and an air pump actuated by the depression of the plunger and adapted to force air through said atomizer to spray said stamps, said air pump serving to retard the movement of the 30 carriage.

4. In a device of the character described, the combination with a supporting frame, of a vertically movable plunger, a spring normally tending to hold said plunger in an elevated position, a longitudinally movable carriage, a cutting edge formed upon said carriage which extends the width of the sheet of stamps to be cut, a feed roller carried by the carriage and adapted to feed said sheet of stamps over said cutting edge, means for moistening said stamps, a ratchet bar journaled for rocking movement upon said carriage, a member actuated by the depression of the plunger and adapted to engage said ratchet bar to impart a step by step 45 longitudinal movement to the carriage, and a stop member for preventing retrograde movement of the carriage.

5. In a device of the character described, the combination with a supporting frame, of a vertically movable plunger, a spring normally tending to hold said plunger in an elevated position, a longitudinally movable carriage, a cutting edge formed upon said carriage which extends the width of the sheet of stamps to be cut, a feed roller carried by the carriage and adapted to feed said sheet of stamps over said cutting edge, means for moistening said stamps, a ratchet bar journaled for rocking movement upon said 50 carriage, and a member actuated by the depression of the plunger and adapted to engage said ratchet bar to impart a step by step 55 longitudinal movement to the carriage.

In testimony whereof I affix my signature 60 in presence of two witnesses.

EDWIN C. YAUCK.
